UNITED STATES PATENT OFFICE.

ANDREW J. SANFORD, OF NEWARK, OHIO.

DESIGN FOR A LIGHT-SHADE.

40,335.

Specification for Design.

Patented Nov. 2, 1909.

Application filed June 25, 1909. Serial No. 504,381. Term of patent 14 years.

To all whom it may concern:

Be it known that I, ANDREW J. SANFORD, a citizen of the United States, residing at Newark, county of Licking, and State of Ohio, have invented a new, original, and ornamental Design for Light-Shades, of which the following is a specification, reference being had to the accompanying drawing, forming a part thereof.

The drawing is a perspective view of a glass light shade showing my new design.

Its leading features consist in a shade body of substantially even flare having a series of longitudinally arranged tapering

prisms alternating with a series of longitudinally arranged, substantially diamond-shaped prisms tapering between them; and a series of short prisms with rectangular faces below each of the above series, as shown.

I claim:

The ornamental design for a light shade, as shown and described.

ANDREW J. SANFORD.
